WATER REPELLENT, METHOD OF IMPREGNATING TEXTILES WITH SAME, AND TEXTILES BEARING SAME

William F. Herbes, Somerville, and Andrews C. Wintringham, Glen Ridge, N.J., assignors to American Cyanamid Company, New York, N.Y., a corporation of Maine

No Drawing. Filed Apr. 12, 1956, Ser. No. 577,673

17 Claims. (Cl. 260—21)

The present invention relates to an improved water-repellent composition, its preferred use in treating textile fabrics and the resultant durably water-repellent fabrics.

Many agents have been suggested for producing a water-repellent finish on various textile fabrics. Comparatively few of these have been commercially successful and many of these are of a nondurable or impermanent nature in that they are removed readily upon washing or dry cleaning. The number of water-repellent agents of a durable nature, that is, capable of standing repeated washing or dry cleaning, is still smaller. Among those which have achieved outstanding commercial recognition in the textile finishing field are those disclosed in Thurston Patent No. 2,357,273. Thurston's dispersions comprise essentially an alkylated methylol melamine such as methylated methylol melamine in combination with certain reactive nitrogenous compounds containing a higher alkyl radical as exemplified by stearamide and methylol stearamide and although they have consistently produced excellent and durable water repellency on cotton and other textile fabrics, certain difficulties and limitations attend their use. They have a marked tendency toward foaming, and this foam is of a dry and stable nature that tends to build up and create difficulties in the pad baths of textile finishing plants. Occasionally, the foam is carried along with the goods being padded which results in spotting, and this sometimes produces a spotted appearance on the treated fabric. In addition, these water-repellent compositions are incompatible with a number of other dispersible and/or soluble textile treating agents such as magnesium chloride, certain dyeing assistants and/or dye fixatives, textile softeners of the type described in Patent No. 2,427,242, and with hard water. This incompatibility manifests itself in the form of separation of the bath constituents or the formation of a creamy layer which spoils the bath for textile treating purposes. Magnesium chloride is currently regarded as the most effective catalyst for curing resinous compositions containing melamine as (1) it greatly reduces the chlorine retention of melamine-formaldehyde treated fabrics, and (2) it greatly improves the efficiency of the resin.

An object of the invention is to provide an improved water-repellent composition.

Another object of the invention is to provide an improved method for producing water-repellent effects on various textile fabrics.

A further object of the invention is to provide textile fabrics having an improved water-repellent finish of a durable nature.

Still another object of the invention is to provide an improved water-repellent composition of greater compatibility with other substances used in the treatment of textiles.

A still further object of the invention is to provide an improved water-repellent composition having less tendency to form a stable or thick foam.

Other objects and advantages of the invention will be apparent upon consideration of the detailed disclosure hereinbelow.

2

The present invention accordingly concerns aqueous dispersions of one or more of certain selected thermosetting resins, one or more compounds having an alkyl radical of at least 7 carbon atoms and containing a nitrogen atom having attached thereto a carbonyl radical and a reactive substituent of the group consisting of hydrogen and alkylol radicals, one or more of certain alkali soaps, and one or more of certain selected nonionic surface-active agents; and also the treatment of textile materials therewith and the resulting durably water-repellent articles. Optional constituents of the above dispersions, which are highly desirable for many purposes, include certain anionic surface-active agents. The preferred resins are methylated methylol melamine resins.

Unless otherwise designated herein, such expressions as long chain or higher alkyl radicals, aliphatic fatty acids and like expressions are used to refer to chains of at least 7 carbon atoms, and especially those containing between about 12 and about 22 carbon atoms, on up to 30 or more carbons in the chain.

The present invention constitutes an improvement over that disclosed in the Thurston patent, especially in connection with the addition of certain selected nonionic dispersing agents but also in the wider range of equivalent thermosetting resin components and the stabilizing effect of certain sulfonated or sulfated surface-active agents. None of the difficulties described earlier are encountered with the present dispersions, and a definitely improved resistance to spotting has been observed. The tendency toward foaming in commercial pad baths is greatly reduced as any foam formed has been found to be of a wetter nature which breaks more easily. Moreover, the present compositions are not substantially affected by dilution with "hard" water, and they are compatible with the aforementioned softener as well as the important class of dye fixatives of the basic cationic complexes. Although dyeing operations are carried out in advance of the present treatment, residual amounts of such copper complexes frequently remain on textile fabrics even after an intervening washing. In addition, many compositions of the present invention are suitable for use with the highly effective magnesium chloride curing catalyst. Besides those mentioned, other benefits obtained in treating textile fabrics with the present compositions are improved abrasion and wear resistance, felting of the fabrics, spot resistance, mildew resistance, durable wrinkle recovery, dimensional stability, maximum tear strength and sewability, reduction of stretching and sagging, longer fabric life and reduction of fabric shift and yarn slippage.

The agents described herein may be employed in the treatment of a wide variety of textile materials as set forth in Thurston Patent 2,357,273, which is incorporated here by reference. These include fibers, threads, yarns, knitted and woven cloth as well as nonwoven fabrics and felted materials. The fibers may be composed of cellulose, cellulose esters, wool, silk, and various synthetic yarns derived from linear super-polyamides such as nylon, homopolymers and copolymers of acrylonitrile, polyesters such as polyethylene glycol terephthalate and various blends thereof. However, the greatest utility and the preferred materials are those containing cellulose fibers such as cotton, viscose and cuprammonium rayons, linen, hemp, jute and ramie, either alone or mixed in a substantial proportion amounting to at least about 25% by weight with other textile fibers.

The hydrophobic nitrogen-containing compounds used in preparing the present water repellent are those described in the aforesaid patent and having the general formula:

70

in which Y is a member of the group consisting of hydrogen and unsubstituted or substituted alkylol radicals, such as methylol or ethylol radicals, Z is a member of the group consisting of oxygen and sulfur, and X and R are members of the group consisting of hydrogen, non-functional substituents, and radicals containing alkyl hydrophobe groups of at least 7 carbon atoms, it being understood that in all cases at least one X or R contains a hydrophobe alkyl radical of at least 7 carbon atoms.

Thurston names a wide range of suitable equivalents which need not be repeated here in full detail except to mention that the preferred groups are the amides of monocarboxylic higher fatty acids like caprylamide, capramide, lauramide, palmitamide, stearamide, and the amides of unsaturated acids such as oleic acid, linoleic acid, ricinoleic acid, etc. Optimum results have been obtained with the saturated higher fatty acids such as stearamide and especially with their N-methylol derivatives.

The resin-forming constituents of the novel compositions include alkylated methylol melamines, alkylated methylol ureas, and methylol alkylene ureas. Of these, the methyl ethers of methylol melamine provide the optimum results, and such may contain from 1 to 6 mols of combined formaldehyde and 1 to 6 mols of combined methanol per mol of melamine; the combined methanol, of course, does not exceed the combined formaldehyde on a molar basis. Typical examples are a 67% methylated trimethylol melamine and a 50% methylated pentamethylol melamine and the alkylated methylol ureas. This term (alkylated methylol ureas) is used herein in its broader sense to include both monomers and their water-soluble low order polymers inasmuch as both are operative. Of these, the partially polymerized methoxy methyl ureas are preferred. Other suitable agents include formaldehyde condensates of alkylene ureas like dimethylol ethylene urea, dimethylol propylene urea, and dimethylol trimethylene urea. These substances and their preparation are well understood and they may contain from 1 to 2 mols of combined formaldehyde per mol of urea or urea derivative as well as a combined methanol content ranging from about 20% up to but not exceeding the formaldehyde content on a molar basis. The water-soluble lower polymers of methylated methylol urea may be easily obtained by refluxing with heating about 2.5 mols of paraformaldehyde per mol of urea in a methanol medium for several hours at an alkaline pH, cooling, adding methanol in stoichiometric excess, adjusting the mixture to a moderately acid pH, refluxing for a short period, then stopping the reaction by cooling and adjusting the pH to a moderately alkaline value.

Based on 100 parts by weight of the hydrophobic nitrogenous compound or compounds (N-methylol stearamide, etc.), the resins described herein may be introduced in an amount ranging between about 40 and about 100 parts and preferably between about 50 and about 200 parts. Mixtures of resins are also suitable as for instance, methylated trimethylol melamine, and dimethylol ethylene urea in a 2:1 weight ratio, and 50% methylated pentamethylol melamine and methylated methylol urea in equal weights.

Another component of the present mixtures is a soap of an alkali metal such as sodium or potassium with one or more of the higher fatty acids. The other alkalies such as an organic amine like triethanolamine are also contemplated for the purpose and are included within the definition of alkali soaps here. The quantity of these soaps appears to be relatively critical since too little has an adverse effect on the stability of aqueous dispersions of the products of this invention and too much tends to produce a rewetting effect on treated cloth which reduces its water repellency. Thus, such soap should be present in amounts ranging between about 4.5 and about 11 parts based on 100 parts by weight of the hydrophobic nitrogen component. A substantial proportion of the required soap is often formed in situ from the free higher fatty

acids like lauric, myristic and stearic which are frequently contained in commercially available hydrophobic nitrogen compounds like stearamide. By the addition of a suitable quantity of sodium or potassium hydroxide, an alkali metal soap is formed within the concentrated aqueous dispersion. However, it is frequently necessary to add an additional quantity of free stearic acid to produce a sufficient quantity of soap.

Nonionic agents suitable for the present invention comprise water-dispersible higher fatty acid esters of sorbitan and more importantly, the nonionic surface-active condensates of an alkylene oxide (propylene oxide or preferably ethylene oxide) with a water-insoluble substance such as the alkyl phenols, higher fatty acids, higher fatty acid esters of sorbitan and higher fatty acid esters of sorbitol. It is to be emphasized that not all nonionic agents are operative to obtain the improved results. The optimum effects are obtained with the alkyl phenols condensed with a plurality of mols of ethylene oxide as for instance, 5 to 50 mols of the latter. Suitable alkyl phenols for preparing these condensates contain from about 7 to about 30 or more carbon atoms in straight or branched chains and excellent examples include octyl phenol, nonyl phenol, lauryl phenol, and octadecyl phenol. The higher fatty acids employed in preparing the aforesaid esters and condensates in known manner may contain from about 8 to about 30 carbon atoms and preferably from about 12 to about 22 carbon atoms as exemplified by lauric, myristic, palmitic, stearic, oleic, ricinoleic, etc. A few of the many operative dispersing agents are the polyoxyethylene derivatives of sorbitan monostearate or monooleate, polyoxyethylenesorbitol laurate or laurate-oleate. These emulsifiers are desirably present in between about 2 and about 20 parts based on 100 parts of the hydrophobic nitrogenous compound.

Optionally and desirably, a sulfonated or sulfated oil may be introduced into the present compositions, preferably in an amount ranging between about 2 and about 15 parts based on 100 parts of said hydrophobic nitrogenous compound. These anionic surface-active materials are produced in known fashion by sulfating or sulfonating either an aliphatic long chain hydrocarbon such as those derived from petroleum oils or the commercial liquid oils from vegetable, marine and animal sources. Coconut, palm, olive, peanut and menhaden may be named as only a few of the suitable oils.

In the present compositions, it is desirable to maintain the total quantity of surface-active components including soap between about 10 and about 35 parts by weight per 100 parts of said hydrophobic nitrogenous compound in order to maintain a dispersion of good stability in either concentrated or dilute form without impairing the water-repellent effects obtained in treating textile fabrics or other materials.

While the compositions hereinbelow are usually prepared as concentrated aqueous dispersions and sold in such form, as for instance, with solid concentrations between about 30 and about 60% by weight, it is desirable to dilute them to between about 0.5 and about 20% solids for application by means of pad baths, spraying or any other suitable means of impregnating textile materials. The textile fabrics are thereafter dried in the usual fashion and cured, and this is most desirably accomplished in a single operation for about 45 seconds to about 20 minutes at a temperature between about 400° F. and about 275° F.

The pickup of solids on the treated fabrics may be varied considerably between about 0.5 and about 20% depending on the effect desired. Light pickups are suitable for providing resistance to spotting or for modification of hand, but for the full water-repellent effect, the solids pickup should be between about 2 and about 10%.

A wide variety of catalysts may be used in conventional amounts ranging between 3 and 40% based on the weight of thermosetting resin component. Among the many suit-

able catalysts are ammonium sulfate, ammonium chloride, diammonium hydrogen phosphate and an organic amine hydrochloride. In the case of magnesium chloride, the quantity is desirably between about 4.5 and 24% of the anhydrous salt and about 9 to about 15% based on the weight of resin is recommended for most purposes.

For a better understanding of the nature and objects of this invention, reference should be had to the accompanying illustrative examples in which all proportions are set forth in terms of weight unless otherwise stated therein. These examples are intended for purposes of illustration and comparison rather than as limiting as to proportions and ingredients.

Example 1

1,710 parts of methylated trimethylol melamine (80% solids), 424 parts of 37% formaldehyde, 1,360 parts of stearamide powder containing 47.6 parts of stearic acid, and 27.2 parts of stearic acid are mixed with stirring until a uniform dispersion is obtained. Then 76 parts of a petroleum sulfonate dissolved in 567 parts of water is added to the dispersion followed by 22.5 parts of potassium hydroxide dissolved in 200 parts of water. This mixture is stirred until smooth, then passed through a heat exchanger equipped with stirring blades at about 104° C., followed by cooling by similar heat exchange means to a temperature of about 25° C. to 35° C. 635 parts of this paste is diluted with a solution containing 13.2 parts of nonyl phenol ethylene oxide adduct (1:9 molar ratio) and 365 parts of water. The mixture is stirred until smooth.

Ten parts of the finished paste are diluted with 80 parts of water. To this dispersion is added 0.2 part of dicyandiamide and 1.6 parts of a 30% solution of magnesium chloride ($MgCl_2$). The pH of the dispersion is adjusted to 6.0 with a 10% solution of NaH_2PO_4 . The dispersion is then made up to a total of 100 parts with water. This dispersion is applied by padding to cotton poplin, viscose rayon challis, cellulose acetate and 50:50 viscose-acetate fabrics which are then passed between rubber squeeze rolls to give a wet pickup of approximately 80%. The treated fabrics are dried and then cured by heating for 90 seconds at 350° F. All of the heat-cured fabrics display a high degree of water repellency which is durable to washing and to dry cleaning.

A second pad bath is prepared by diluting 10 parts of the finished paste with 84.8 parts of water. To this dispersion is added 0.2 part of dicyandiamide and 5 parts of a 20% solution of ammonium sulfate as the curing catalyst. The dispersion is applied to all of the fabrics described above. These treated fabrics have finishes with substantially the same water repellency and durability to washing and to dry cleaning.

Example 2

Example 1 is repeated using 13.2 parts of polyoxyethylene sorbitan mono-oleate, a nonionic surface-active agent, in place of the nonionic adduct.

The finished paste is applied to cotton poplin and rayon challis as before. The finishes on these cured fabrics are almost equal in durability and water-repellent characteristics to those obtained in the preceding example.

Comparative Example A

The procedure of Example 1 is repeated substituting 13.2 parts of a well-known nonionic polyoxyalkylene ether of a higher alkyl branched chain alcohol dispersing agent in place of the nonyl phenol-ethylene oxide condensate.

The finished paste is made into two pad baths as previously described, using magnesium chloride and ammonium sulfate as the catalysts, but these baths are unsuitable for textile treating due to flocculation and separation.

Comparative Example B

Again the procedure of Example 1 is duplicated with 13.2 parts of a different nonionic surface-active agent, namely, the condensate of ethylene oxide with a hydrophobic compound formed by condensing propylene oxide with propylene glycol, in place of the adduct of nonyl phenol with ethylene oxide. This composition is unsatisfactory as a waterproofing agent because a pad bath made with ammonium sulfate as the catalyst shows flocculation and separation.

Example 3

Again a composition is compounded according to Example 1 with 13.2 parts of nonionic polyethylene glycol 600 monolaurate replacing the aforesaid nonionic adduct. The finished paste is applied in the same manner to samples of cotton poplin and rayon challis using ammonium sulfate as the catalyst. The treated fabrics have a durable finish with a good spray rating.

Example 4

The composition of Example 1 is changed by the selection of 13.2 parts of polyoxyethylene sorbitol oleate-laurate as the non-ionic surface-active agent. Upon applying the paste in an ammonium sulfate catalyzed pad bath as before to cotton poplin and rayon from the same source, the fabrics after curing are found to have good water-repellent characteristics in a finish which is durable to dry cleaning and washing.

Example 5

Example 1 is repeated in full except for the substitution of 13.2 parts of sorbitan monolaurate as the nonionic emulsifier instead of the nonyl phenol-ethylene oxide condensate. Two pad baths are prepared from the paste, one containing magnesium chloride and the other ammonium sulfate as the accelerator, and the heat-cured finishes on samples of the same cotton poplin and rayon challis are found to be highly water repellent, and this characteristic is retained after washing and dry cleaning.

Example 6

A water-repellent agent is compounded as in Example 1 with a different resin component. An 80% aqueous dispersion of methylated partially polymerized dimethylol urea (80% of the methylol groups being methylated) is used in lieu of the same weight of methylated trimethylol melamine on an equivalent solids basis. After treating the same cotton poplin and rayon challis according to Example 1 in a pad bath containing ammonium sulfate, the resulting textile products are found to have good water-repellent characteristics in the durable finish.

Example 7

55 A water-repellent composition is compounded according to Example 1 with 19 parts of lauric acid substituted in place of 27.2 parts of the stearic acid used therein. No substantial change in results is observed on any of the treated fabrics using both catalysts.

Example 8

Example 1 is repeated in full using the composition wherein 27.1 parts of oleic acid are employed instead of 27.2 parts of stearic acid. The characteristics of the fabrics treated with this agent are the same in all respects to those obtained in Example 1.

Example 9

Ten parts of the finished paste prepared as described in Example 1 is diluted with 42.8 parts of water. To this dispersion is added 0.2 part of dicyandiamide, 42 parts of a solution containing 2 parts of a basic cation-active copper complex compound and 40 parts of water, and 5 parts of a 20% solution of ammonium sulfate. This smooth dispersion is applied to cotton poplin as de-

scribed under Example 1. The treated fabric displays good water repellency and the finish is durable to washing and dry cleaning.

Example 10

2,710 parts of dimethylol ethylene urea (50% solids), 424 parts of 37% formaldehyde, 1,360 parts of stearamide powder containing 47.6 parts of stearic acid and 27.2 parts of stearic acid are mixed with stirring until a uniform dispersion is obtained. 76 parts of a petroleum sulfonate is dissolved in 567 parts of water and this solution is added to the dispersion. 22.5 parts of potassium hydroxide is dissolved in 200 parts of water and this solution is also added to the dispersion. The mixture is stirred until smooth, and heated and cooled as in Example 1. 1,270 parts of the paste is diluted with a solution containing 26.4 parts of nonyl phenol ethylene oxide adduct and 730 parts of water. The mixture is stirred until smooth.

pregnated material to cure the finish to the substantially water-insoluble state whereby a durable water-repellent finish is imparted to the textile material.

15. An article which comprises a durably water-repellent textile material bearing the water-insoluble product of curing a composition according to claim 1 with magnesium chloride.

16. An article which comprises a durably water-repellent textile material bearing the water-insoluble product of curing a composition according to claim 2 with magnesium chloride.

17. An article which comprises a durably water-repellent textile material bearing the water-insoluble product of curing a composition according to claim 3 with magnesium chloride.
